CLAIM

The ornamental design for a hermaphroditic electrical terminal for an electrical receptacle as shown and described.

DESCRIPTION

FIG. 1 is a perspective view of a hermaphroditic electrical terminal for an electrical receptacle showing my new design; FIG. 2 is a top view thereof; FIG. 3 is a bottom view thereof; FIG. 4 is a side view thereof; FIG. 5 is an opposite side view thereof; FIG. 6 is an end view thereof; FIG. 7 is an opposite end view thereof; FIG. 8 is a perspective view of another embodiment of the hermaphroditic electrical terminal for an electrical receptacle showing my new design; and, FIG. 9 is a top view of the embodiment shown in FIG. 8.

1 Claim, 8 Drawing Sheets
